(57) **CLAIM**

The ornamental design for a wrapper for a bottle or glass, as shown and described.

DESCRIPTION

FIG. 1 is a front elevational view of the wrapper for a bottle or glass showing my new design;

FIG. 2 is a rear elevational view of the wrapper for a bottle or glass thereof;

FIG. 3 is a left-side elevational view of the wrapper for a bottle or glass thereof;

FIG. 4 is right side elevational view of the wrapper for a bottle or glass thereof;

FIG. 5 is a top plan view of the wrapper for a bottle or glass thereof; and,

FIG. 6 is a perspective view of the wrapper for a bottle or glass thereof.

The dash dot dot dash broken line showing a baby bottle is included for the purpose of illustrating environmental structure that forms no part of the claimed design.
